United States Patent Office

Des. 187,693
Patented Apr. 19, 1960

187,693

NAIL STUD

John W. Frey, Carmel Valley, and Ernest R. Rutzke,
Sharp Park, Calif., assignors to Frey & Hartel, Inc.,
San Francisco, Calif., a corporation of Illinois

Application January 27, 1958, Serial No. 49,423

Term of patent 14 years

(Cl. D13—1)

Fig. 1.

Fig. 2.

Fig. 3

Fig. 4.

Fig. 1 is a perspective view of a nail stud showing our new design as viewed from one side and above;

Fig. 2 is a vertical edge view thereof;

Fig. 3 is a perspective view thereof viewed from the other side and top; and

Fig. 4 is a top plan view thereof.

Figs. 1, 2 and 3 shown broken away in the center thereof represent indeterminate length.

We claim:

The ornamental design for a nail stud, as shown and described.
